ATTORNEY

UNITED STATES PATENT OFFICE

2,485,313

BRASSIÈRE

Harry Rabinowitz, New York, N. Y.

Application May 17, 1947, Serial No. 748,723

1 Claim. (Cl. 2—42)

1

This invention relates to a nursing brassière and particularly to a construction employing a service covering flap and means for adjusting the pockets to provide accommodation corresponding with the dimensional changes of the bust of the mother, and one of the objects of the invention is to provide a flap or cover which when moved to open position will relieve the breast of external pressure during the period of nursing.

Another object of the invention is to provide a design for the flap or cover which will provide a cupped body having the molding seam located to provide auxiliary support for the bust.

Another object of the invention is to improve the means for adjusting the support given to the bust to insure that the best adjustment will be available at all times and release may be made without confusion.

For further comprehension of the invention and of the objects and advantages thereof, reference will be had to the following description and accompanying drawings, and to the appended claim in which the novel features of the invention are more particularly set forth.

In the accompanying drawings forming a material part of this disclosure:

Fig. 1 is a front elevation of the improved nursing brassière.

Fig. 2 is a rear elevation of the brassière.

Fig. 3 is a detail plan view of one of the covering flaps, showing the molding seam thereof.

Fig. 4 is a detail cross sectional view, taken on line 4—4 of Fig. 3.

Fig. 5 is a detail plan view, enlarged, of one of the supporting strips, showing the adjustment means thereof.

Fig. 6 is a detail longitudinal sectional view, taken on line 6—6 of Fig. 5, looking in the direction of the arrows.

Fig. 7 is a detail plan view, enlarged, of the means used for girth adjustment.

Fig. 8 is a detail sectional view, taken on line 8—8 of Fig. 7.

Referring to the drawings, which illustrate the practical embodiment of the invention 10 designates a left wing and 11 the right wing of a nursing brassière, the two wings being permanently united by a central vertical seam 12.

The wing 10 is formed with a circular bust opening 13, the marginal edge of which is reinforced by a lace binding 14, and the wing 11 is formed with a circular bust opening 15, the marginal edge of which is reinforced by the lace binding 16. The adjacent portions of these openings have a permanent supporting function and

2

do not expand to cause a displacement of the bust, or to change the center of feeding.

The wing 10 progressively narrows toward its outer end and is provided with connecting hooks 17, and the wing 11 progressively narrows toward its outer end and is furnished with an elastic webbing 18, the outer end of which carries the strip 19, which is furnished with an inner pair of connecting eyes or loops 20 and an outer pair of connecting eyes or loops 21, which connect with the hooks 17.

The left wing 10 is provided with a shoulder strap 22, one end 22^a of which is secured to the outer end of the wing, and the other end 22^b of which is secured to the widened inner part 10^a of the wing which is formed with the bust opening 13.

The right wing 11 is provided with a shoulder strap 23, one end 23^a of which is connected to the outer end of the wing, and the other or inner end of which is connected to the widened part 11^a, in which the bust opening 15 is formed. The shoulder strap 22 is provided with a buckle 24 for adjustment, and the shoulder strap 23 is provided with a buckle 25 for adjustment.

The bust opening 13 is normally covered by means of a flap 26, which is permanently secured to the wing 10 by means of stitching 27 which extends along the upper marginal edge of the wing, and by stitching 28, which is parallel to the central connecting seam 12. The lower edge 26^a of the flap 26 and the upper outer edge 26^b thereof are wholly unattached to the wing 10, so that the entire flap 26 may be folded toward the hinge joints established by the stitching 27 and 28, inwardly of the breast, from the left to the right side of the body. In this way the bust at the moment of maximum loading will be released for feeding with minimum of restraint, and no central interference.

The flap 26 is cupped to provide comfortable accommodation for the bust organ received by it, and this is done by forming a slit through the lower edge of the flap, and then joining the edges 29 and 30 to each other by a vertical seam 31, which extends from the lower edge to the center of the cup thus formed. This central seam provides reinforcement for the flap and lies normally under the bust engaged.

The opening 15 is normally closed by means of the flap 32, which is of similar construction to the flap 26, being permanently secured at its upper edge 32^a to the upper edge of the wing 11, and at 33 to the central seam 12. The outer upper edges 32^b and the lower edge 32^c are wholly un-

attached to the wing 11. The flap is cupped by a central seam 34, which provides central reinforcement or support for the bust. The flap opens fully to disclose the bust and relieve it of external restraint, by swinging toward the left side of the body.

The outer end of the flap 26 is provided with a hook 35, which is adapted to be coupled to either one of the eyes or connecting loops 36, secured by the strip 37 to the wing 10. The outer end 10 of the flap 32 is provided with a hook 38, which may be connected to either one of the eyes or loops 39 of the strip 40, secured to the wing 11.

The eyes or loops 36 and the eyes or loops 39 are of similar construction and the mounting of one is a duplication of the mounting of the other. Each eye is secured in place by a U-fold 42 of its strip, so that the anchoring base of the eye or loop is entirely enclosed, this U-fold being stitched in place, leaving the terminal portion of the eye alone exposed, so that the hook cannot engage any other part of the member.

The eyes or loops 20 are connected in place in a similar manner, by means of U-folds 19 of the strip 19, so that the anchoring base portions of the eyes or loops will be concealed from view, and not exposed to engagement with the hooks 17.

The mother, wearing the improved nursing brassière, will be able to expose either breast for feeding, which corresponds to the natural position when the infant is held in the arms, and the head is naturally supported to one side of the breast. The bounding edge of the opening un-covered will provide effective support for the breast while nursing.

Each flap is centrally reinforced by means of a circular patch 43. This patch is secured to the inner side of the flap and reinforces the seam of the flap, so that the cup is protected against opening under strain.

While I have illustrated and described the pre-

ferred embodiments of my invention, it is understood that I do not limit myself to the precise constructions herein disclosed, and the right is hereby reserved to all changes and modifications coming within the scope of the invention, as defined by the appended claim.

Having thus described my invention, what I claim as new, and desire to secure by United States Letters Patent is:

In a nursing brassière having an opening through which a breast projects for nursing, a flap fixedly secured at one end along a vertical line and partially along its top edge to the center of the brassière at one side and above the opening and having its free end extended across the opening closing the same, said flap having its bottom edge extended horizontally and its top edge from the end of its attached portion extended downward and outward forming a narrowed down end portion at the free end of said flap of substantially less than half the width of said flap, an elastic webbing attached at one end to the narrowed down end portion of said flap, horizontally spaced eyelets mounted on the side of said brassière on the side of the opening opposite the attached end of said flap, and a hook mounted on the free end of said elastic webbing and selectively engageable with one of said eyelets for adjustably holding the narrowed down end portion of said flap in position.
